UNITED STATES PATENT OFFICE.

PETER MURRAY McKAY, OF NELSON, NEW ZEALAND.

ARTIFICIAL LIMB.

1,319,884.

Specification of Letters Patent.

Patented Oct. 28, 1919.

Application filed October 31, 1917. Serial No. 199,400.

To all whom it may concern:

Be it known that I, PETER MURRAY Mc-
KAY, a subject of the King of England, re-
siding in Nelson, New Zealand, have invent-
5 ed certain new and useful Improvements in
Artificial Limbs, of which the following is
a specification.

This invention relates to improvements in
artificial limbs, and has particular reference
10 to an artificial hand of the kind in which
the fingers are composed of rubber and fab-
ric, each finger being stiffened with a central
wire, and a pivoted thumb of hard material
is normally held in the closed or gripping
15 position by a spring, and is opened by a
cord or other flexible member connected to
a part of the wearer's body. The fingers of
such a hand are bent or straightened by the
other hand of the wearer as occasion re-
20 quires, and one object of this invention is
to provide a construction which will enable
the central wires of the fingers to be readily
replaced when worn out. To that end, the
fingers are hollow and the stiffening wire
25 can be inserted therein and withdrawn
through an opening provided in the hand.
The openings for the stiffening wires are
preferably located in the end of the wrist,
and the end of each wire can be connected
30 by a screw to a metal plate, which is em-
bedded in the hand.

At the wrist, the hand can be provided
with a cylindrical plug adapted to be in-
35 serted in a socket member attached to the
wearer's arm, and a spring catch is provided
at the wrist of the hand adapted to engage
any one of a series of holes located in the
socket member and concentric with the
40 socket. Thus the angular position of the
hand relatively to the socket member can be
adjusted, and held in the desired position by
the spring catch engaging one of the holes.

A thumb is provided to the hand, and is
normally held in the closed or gripping po-
45 sition by a tension spring connected at one
end to the palm of the hand and at the other
end connected between the end of the thumb
and its pivot. The tension spring can be
connected to the stiffening wire in the index
50 finger, and thus it can readily be removed
and replaced by a longer or shorter spring
if desired. A flexible member such as a cord
is connected to the basal end of the thumb
and passes over a pulley situated on the
55 wrist of the hand in such a position that the
cord when pulled rocks the thumb against

the tension of the spring. The cord passes
up outside the wearer's arm, across his back,
and thence across his chest, and is finally
connected to a shoulder pad; guide pulleys 60
being provided at the elbow and shoulder.
By a suitable movement of the muscles of
the chest and shoulder the cord can be
caused to exercise a pull on the thumb and
open it to the desired extent. 65

In the accompanying drawing,

Figure 1 is an elevation of the back of an
artificial hand according to this invention,

Fig. 2 is a side elevation partly in section,

Fig. 3 is a section on the line 3—3 in Fig. 70
1, and

Fig. 4 shows the hand and the thumb op-
erating flexible member in position on the
wearer.

The fingers A of rubber and fabric have 75
a central hole B in which a wire C of non-
resilient metal such as soft copper is inserted
from the end of the wrist. The wire is
formed with an eye D at one end through
which a screw E can be inserted and screwed 80
into an angle plate F set in a wooden block
G which forms the base and wrist portion
of the hand. A plate H is fixed on the end
of the wrist by a small screw I and a cylin-
drical plug J both of which screw into the 85
angle plate F. The plug J is a good fit in
a hole in a socket member K which is con-
nected to the stump of the arm of the wearer,
and when the plug is pushed home an annu-
lar groove J¹ on the plug engages with a 90
spring catch K¹ on the socket member K.
This spring catch K¹ can be of the kind de-
scribed in British patent specification No.
13067 of 1916 but any known type of catch
can be used which is adapted to engage with 95
the groove J¹ and hold the hand firmly in
the socket and which can be moved to re-
lease the hand when desired. The hand can
be rotated in the socket member K, its an-
gular position being fixed by a spring catch 100
L, the pin M of which is adapted to enter
any one of the holes N formed on the out-
side of the socket member in a series concen-
tric with the hole which receives the plug
J. The spring catch L is mounted on the 105
plate H, and pressure on the finger piece O
compresses the spring P and thus lifts the
pin M out of the holes N.

In the thumb Q a metal plate R is em-
bedded and provided with two ears S which 110
are pivotally connected to two ears extend-
ing from a plate T embedded in the palm

of the hand. A tension spring U is connected at one end to the plate R and at the other end is connected to the stiffening wire in the index finger. A cord V is connected 5 at one end to the base of the thumb and passes between the pulleys W, the other end of the cord being provided with an eye X. After the hand is connected to the socket, the eye X is connected to a strap Y (Fig. 10 4) which in turn is connected to a cord Y¹ passing successively over pulleys Z and Z¹ and then joining to a strap Y² which after passing across the back and the chest of the wearer is connected to the shoulder pad Y³. 15 A strap Y⁴ is connected to the strap Y² where it passes under the armpit, and the said strap Y⁴ is connected to a waist-band or the like so as to relieve the upward pressure of the strap Y² under the armpit. It 20 will be obvious that a suitable movement of the muscles of the chest and shoulder will move the cord over its pulleys and cause the thumb to open against the tension of its spring.

25 What I claim as my invention and desire to secure by Letters Patent is:—

1. An artificial hand comprising hollow fingers composed of rubber and fabric; and renewable stiffening wires separately insertible 30 into and withdrawable from the hollow in each finger without impairing the hand, for the purpose described.

2. An artificial hand comprising hollow fingers composed of rubber and fabric; re-

newable stiffening wires separately insertible into and withdrawable from the hollow in each finger without impairing the hand; a metal plate embedded in the hand; and means to connect the end of each wire to said plate after said wires are inserted, said means being accessible from the outside of the hand; for the purpose described. 35 40

3. In an artificial hand, the combination of hollow fingers composed of rubber and fabric; renewable stiffening wires separately 45 insertible into and withdrawable from the hollow in each finger without impairing the hand; a thumb pivoted intermediate its ends to the hand; a tension spring connected at one end to the palm of the hand and at its other 50 end to the thumb on one side of its pivot; and a flexible member operatively connected to the thumb on the other side of the pivot.

4. In an artificial hand, the combination of hollow fingers composed of rubber and fabric; renewable stiffening wires separately 55 insertible into and withdrawable from the hollow in each finger without impairing the hand; a thumb pivoted intermediate its ends to the hand; a tension spring connected at one end to one of the finger wires and at its other end to the thumb on one side of its pivot; and a flexible member operatively connected to the thumb on the other side of the pivot. 60 65

In testimony whereof I affix my signature.

PETER MURRAY MCKAY.
